UNITED STATES PATENT OFFICE.

ISAAC L. MARKS, OF SAN FRANCISCO, CALIFORNIA.

RADIATOR AND SIGHT-TUBE FOR MOTOR-VEHICLES.

1,316,847.

Specification of Letters Patent. Patented Sept. 23, 1919.

Application filed July 2, 1918. Serial No. 243,087.

To all whom it may concern:

Be it known that I, ISAAC L. MARKS, a citizen of the United States, residing at San Francisco, in the county of San Francisco and State of California, have invented certain new and useful Improvements in Radiators and Sight-Tubes for Motor-Vehicles, of which the following is a specification.

10 This invention relates to an improved radiator and sight tube for motor vehicles and has as its primary object to provide an arrangement wherein the sight tube will be built into the construction of the radiator 15 and operatively connected therewith so that the level of the water in the radiator may be easily ascertained by consulting the sight tube.

20 The invention has as a further object to provide an arrangement wherein the sight tube will lie wholly within the lines of the radiator casing so that possibility of accidental injury to the sight tube will be accordingly reduced to a minimum.

25 The invention has as a still further object to provide a construction wherein the sight tube will be inclosed within a suitable casing therefor and wherein an improved mounting for the casing will be employed, 30 acting to center the casing around the tube.

35 And a still further object of the invention is to provide a construction wherein, when desired, the sight tube may be readily removed so that in case of accidental injury to the tube, it may be readily renewed.

40 Other and incidental objects will appear as the description proceeds. In the drawings wherein I have illustrated the preferred embodiment of the invention, and 45 wherein similar reference characters designate corresponding parts throughout the several views:

Figure 1 is a front elevation of my improved radiator and sight tube,

50 Fig. 2 is a fragmentary sectional view showing the manner in which the sight tube is connected at its upper end with the radiator casing,

55 Fig. 2^a is a view similar to Fig. 2 and showing the manner in which the sight tube is connected at its lower end to the radiator casing, and

60 Fig. 3 is a fragmentary transverse sectional view taken on the line 3—3 of Fig. 55 2 and showing the manner in which the cas-

ing of the radiator is recessed to receive the upper end portion of the sight tube.

Referring more particularly to the drawings, I employ a radiator 10 having a casing 11, the upper portion of which is formed 60 medially of its front face with an inwardly directed recess 12 preferably arcuate in cross section, as particularly shown in Fig. 3. The body of radiating cells of the radiator may be of any approved character. Depending from the top wall of the recess 12 axially thereof is a nipple 13 upon which is screw threaded a coupling nut 14. Rising from the inner side wall of the bottom portion of the radiator casing is a similar 70 nipple 15 arranged in vertical alinement with the nipple 13 and threaded to receive a coupling nut 16. Snugly fitting between the nipples 13 and 15 to communicate therethrough with the radiator casing is a 75 sight tube 17 surrounded at its ends by suitable resilient packing washers 18 received within the coupling nuts 14 and 16 and clamped by the said nuts to tightly seal the sight tube in position. Surrounding the sight tube is a protecting sleeve or 80 casing 19 therefor. Between the ends of this tube and the coupling nuts 14 and 16 are interposed collars 20 snugly surrounding the sight tube. These collars are 85 constructed of rubber or other compressible material and upon the inner ends thereof are formed with annular flanges 21 fitting within the ends of the casing and acting to center the casing around the sight tube. 90 At the same time, the collars will act to center the casing longitudinally with respect to the tube and will resiliently bear against the ends of the casing to prevent any looseness or rattling thereof as well as to also 95 prevent axial rotation of the casing. The casing 19 is formed upon the front side thereof with a longitudinally extending slot 22.

Attention is now directed to the fact that 100 the sight tube and associated parts are disposed wholly within the lines of the radiator so that the possibility of accidental injury to the sight tube will be reduced to a minimum. Since the tube is in communication 105 at its ends with the top and bottom portions of the radiator casing, water within the radiator will, of course, rise within the sight tube so that the level of the water in the radiator may thus be easily determined by 110

consulting said tube through the slot 22 in the front of the tube casing. I thus provide a particularly simple and efficient construction for the purpose set forth. Should the 5 sight tube become accidentally broken or should it, for any reason, be desired to remove the said tube, it will be noted that the collars 20 at the ends of the casing 19 are relatively thick and may accordingly be 10 compressed sufficiently to allow the removal of the coupling nuts 14 and 16. After these nuts have been removed, the tube and its casing may be readily displaced. The sight tube may consequently be easily cleaned or 15 renewed.

Having thus described the invention, what is claimed as new is:

1. A device of the character described including spaced supporting nipples, a sight tube extending between said nipples, means carried by the nipples and connecting the tube therewith, a casing surrounding the sight tube, and means interposed between the confronting inner ends of said connecting 20 means and the casing exteriorly of said connecting means for centering the casing with respect to the tube.

2. A device of the character described in-

cluding a sight tube, supporting means therefor, a casing surrounding the tube, 30 means carried by said supporting means and connecting the tube therewith, collars surrounding the tube and bearing between the ends of the casing and the confronting inner ends of said connecting means for supporting 35 the casing longitudinally with respect to the tube, and flanges formed on the inner ends of said collars and fitting within the ends of the casing for centering the casing with respect to the tube. 40

3. A device of the character described including a sight tube, supporting means therefor, means adjustable upon said supporting means and connecting the tube therewith, a casing surrounding the tube and 45 independent of said connecting means, and means bearing between the connecting means and the ends of the casing for supporting the casing exteriorly of said connecting means with respect to the tube, said latter 50 means being compressible whereby said connecting means may be adjusted toward each other and freed from said supporting means.

In testimony whereof I affix my signature.

ISAAC L. MARKS. [L.S.]
